DRIVE-IN RESTAURANT

Henry R. Harrison, Pacific Palisades, Calif., assignor to A & W Root Beer Co., Santa Monica, Calif., a corporation of California

Filed July 13, 1964, Ser. No. 38,815

Term of patent 14 years

(Cl. D13—1)

FIGURE 2 is an end view taken from the right of FIG-URE 1; and

URE 1.

The top view of the drive-in restaurant is plain.

The shape and appearance of the undisclosed side opposite to that shown in FIGURE 1 is the same as that shown in FIGURE 1, except for a conventional door.

I claim:

The ornamental design for a drive-in restaurant, substantially as shown and described.
